BOX

William R. Looney, Los Angeles, Calif., assignor
to Harry Bergman, John B. Horbach, and J.
Arthur Greenfield, Los Angeles, Calif.

Application December 1, 1934, Serial No. 755,596

2 Claims. (Cl. 229—36)

This invention relates to boxes and more particularly to a cardboard box and means for securing the box in closed condition so that the box cannot be opened once it has been locked without showing that the box has been opened or tampered with.

An object of this invention is to provide a blank form which can be formed into a suitable container having regular or irregular walls and the container having means whereby the ends thereof may be conveniently locked so as to prevent tampering with the contents of the box without showing that the box has been broken into.

Another object of this invention is to provide a form for folding into a box whereby the box before being finally closed will form a hopper-like portion to facilitate filling of the box, and in this position, the ends of the box are securely locked against spreading.

A further object of this invention is to provide a box structure of this kind wherein the ends of the box are reinforced by a number of thicknesses of material, the material being formed from each side, the bottom and the top of the device, and an additional thickness being carried by one of two top members so that there will be at least five thicknesses of material on each end, and the different thicknesses are so positioned relative one to another that the locking means for the container at each end is concealed, thereby making it impossible to separate the different portions of the box without breaking the locking means.

The above and various other objects and advantages of this invention will in part be described and in part be understood from the following detailed description of the present preferred embodiment, the same being illustrated in the accompanying drawings wherein:

Figure 1 is a plan view of the blank used for forming a box constructed according to the embodiment of this invention, the box having regular sides, bottom and top, so as to form a substantially square end.

Figure 2 is a modified form of the blank wherein the top and bottom are of a width different from the sides so that the ends will form a rectangle.

Figure 3 is a fragmentary perspective view showing the initial step in the folding or assembling of the box shown in Figure 1.

Figure 4 is a fragmentary perspective view showing the second step in the closing of the box and also showing the hopper-like formation of

the two top members so as to facilitate the filling of the box.

Figure 5 is a fragmentary perspective view showing the box in closed position.

Figure 6 is a fragmentary sectional view taken on the line 6—6 of Figure 5.

Referring to the drawings and first to Figure 1, the letter B designates generally a box structure formed of a single sheet of cardboard or other composition material which is relatively stiff. This box structure B comprises a substantially rectangular sheet of material which is divided into a top section 10 disposed at one end of the rectangular sheet, and a second top section 11 is disposed at the other end of the rectangular sheet. A side member 12 is connected to the top section 10 and a second side member 13 is connected to the top section 11, and a bottom wall or section 14 is disposed between the two side walls or sections 12 and 13. If desired, the material of the box B may be either scored or otherwise formed between the various wall sections so as to facilitate the bending of these sections one relative to another in order to form the box which is shown in Figure 5 in closed position.

The top wall 10 has formed therewith end wall members 15, one at each end of the top wall 10, and additional end wall members 16 are integral with the end walls 15. The top wall 10 and each end wall 15 may have therebetween scores 17 or the like, so as to facilitate the bending of the walls 15 and scores or suitable means 18 may also be disposed between the two end wall members 15 and 16, so as to facilitate the bending of these walls one relative to another.

A locking tongue 19 is carried by the side wall member 12, there being two of these tongue members 19 one at each end of the side 12. The other side wall 13 has end wall members 20 integral therewith, which are bendable along the line 21. These end wall members 20 have a substantially diagonally extending tongue 22 struck from the body thereof adjacent one of the inner corners of the end wall 20 with the free portion of the tongue 22 outermost.

The bottom wall or member 14 has end wall members 23 integral therewith one at each end of the bottom, and the end members 23 are bendable along the line or score 24. The end wall members 23 have an inwardly directed tongue 25 struck from the body thereof disposed in substantially the center of the wall 23, and a similar tongue 26 is struck from the end wall member 16 of the top 10.

As will be noted from the drawings, the top wall member 11 does not have any end walls secured to or integral therewith.

In the assembly or formation of the box from the blank disclosed in Figure 1, the top wall 11 together with the side wall 13 may be bent upwardly along the line or score 27 which is disposed between the bottom 14 and the side 13, and then the end wall members 20 may be bent along the line or score 21 at substantially a right angle to the length of the side 13. At the same time, the end wall members 23 may be bent at substantially a right angle to the bottom member 14 along the line 24, and the bottom end wall member 23 is preferably disposed inside the end wall member 20. Figure 3 shows the box in the stage of formation just described.

After the side 13 and the top member 11 have been bent upwardly at a right angle to the bottom 14, the top member 10 and the side member 12 may be bent upwardly along the line or score 28 disposed between the side 12 and the bottom 14. At this time, the locking member 19 is bent inwardly or at a right angle to the side member 12 along the line 29 so that the locking portion or lip 30 may be passed through the slot 31 formed by striking the tongue 22 from the end wall 20. Preferably, the locking portion 30 is passed over and on the outside of the tongue 22 and then inwardly between the end wall 20 and the end wall 23. The angular lip portion 32 is adapted to engage behind or inwardly of the tongue 22. In this position, the two top wall members 10 and 11 are disposed in spaced parallel relation to each other and together with the end wall members 15 and 16 form a hopper by means of which the interior of the box may be readily filled. It will be noted that at this stage of the formation of the box, the two side wall members 12 and 13 are locked against movement relative to each other so that when the interior of the box is filled, there will be no spreading movement whatever between the two side walls caused by opening of the locking means for the ends of the box.

After the box has been filled to the height of the side members 12 and 13, the top member 11 may be first bent at a right angle to the side 13, it being understood that the end wall members 15 and 16 are at this stage moved outwardly so as to permit the top member 11 to be moved downwardly at a right angle to the side member 13. The top member 11 is bent along the line 33 between the side 13 and the top 11. In order to hold the top member 11 in position, the outside top member 10 is then bent along the line 34 between the side 12 and the top 10 and then the end wall members 15 and 16 are bent at substantially a right angle to the closed outer top 10 and the outermost end wall member 16 is then inserted between the inner end wall member 23 and the locking wall member 20. Movement of the wall member 16 between the end wall 23 and the end wall 20 will bring the locking tongue 26 into register with the slot formed by the locking tongue 25, so that the locking tongue 26, as shown in Figure 6, will extend into the slot formed by striking the tongue 25, and will be locked there-

by. The end wall 25, as will be noted from Figure 5, will be disposed on the outside of the layers of material forming the ends of the box, and will cover up the locking members 19 and 20.

In Figure 2, I have shown a box structure which is similar to the box structure shown in Figure 1, but in this figure, the outer top wall 10' is relatively wide with relation to the side wall 12'. The inner top member 11' is also the same width as the top 10' and is wider than the side wall member 13', whereas the bottom 14' is of the same width as the two top members 10' and 11'.

The top member 10' has end members 15' and 16' at each end and the side member 12' has locking members 19' which are similar to the locking members 19. The bottom 14', however, has a wall member 23' and a second end wall member 35 is integral with the end wall member 23' and is bendable along the line 36. This wall member 35, when the box is assembled, will be an inner end wall and will act as an additional reinforcing means at the end of the box. An end wall member 20' is carried one at each end of the side 13' and each end wall 20' has a locking tongue 22' struck from the body thereof after the manner of the tongue 22.

The box formed by the modification shown in Figure 2 is assembled in the same manner as the box shown in Figure 1.

Through the use of a box constructed as hereinbefore described, it is possible to securely seal the contents within the box so that there can be no tampering of the contents without such tampering being discernable as in order to open the box, it will be necessary to pull the end wall member 16 out from between the end wall 20 and the end wall 23, thereby tearing the locking tongue 26.

What is claimed is:—

1. A box, comprising a single sheet of material having integral sides, bottom and a pair of top members, a pair of end walls carried one at each end of the bottom member, interengaging end wall members carried by the side members, pairs of connected end wall members secured at an end of one of the top members, there being one pair at each end of said one top member, the outermost of said pair of connected end wall members being insertable between the bottom end member and said interengaging end wall members, and interlocking means carried by said outermost end wall member and said bottom end wall member.

2. A box, comprising a single sheet of material having integral sides, bottom and a pair of top members, a pair of end walls carried one at each end of the bottom member, end wall members carried by the side members, interlocking means carried by said side end wall members, pairs of connected end wall members secured at an end of the top members, there being one pair at each end of said one top member and the outermost of said pair of connected end wall members being insertable between the bottom end member and one of said side end wall members, and interlocking means carried by said bottom end wall member and said outermost end wall member.

WILLIAM R. LOONEY.
